UNITED STATES PATENT OFFICE

OMER J. POULIN, OF LEWISTON, MAINE

BROOM HOLDER

Application filed August 26, 1930. Serial No. 477,944.

The present invention relates to a broom holder and has for its prime object to provide a device which may be nailed or otherwise fastened to the wall or the like for the purpose of holding brooms, mops and the like.

Another very important object of the invention resides in the provision of a device of this nature which is exceedingly simple in its construction, inexpensive to manufacture, strong and durable, and thoroughly efficient and reliable in use.

With the above and numerous other objects in view as will appear as the description proceeds, the invention resides in certain novel features of construction, and in the combination and arrangement of parts as will be hereinafter more fully described and claimed.

In the drawings:

Figure 1 is a perspective view of the device embodying the features of my invention, and

Figure 2 is an end elevation thereof.

Referring to the drawings in detail it will be seen that the numeral 5 denotes a plate having the reduced end portions at the top and bottom thereof as denoted respectively by numerals 6 and 7 to form ears and having opening 8 and 9 therein for the purpose of fastening elements so that the plate may be secured to the wall or like supporting structure.

A central longitudinal block 10 is fastened in any suitable manner on the central plate 5 and has concaved sides 11. A rectangular plate 12 is secured to the outside of the block 10 and overlaps the sides thereof. Side blocks 14 are fastened to the sides of the plate 5 and have plates 15 fastened thereon to extend inwardly of the blocks 10. Disks 16 are disposed between the blocks 10 and 14 and are prevented from displacement by the plates 12 and 15 and also are of greater diameter than the width between the nearer portions of the block 10 and adjacent portions of the blocks 14.

Therefore a broom handle or the like 17 may be mounted as is clearly illustrated in Figure 1 of the drawings.

It is thought that the construction, utility and advantages of this invention will now

be quite apparent to those skilled in this art without a more detailed description thereof.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

A device of the class described comprising a plate having a central block thereon and a pair of side blocks in spaced relation to the central block, said central block having its edges adjacent the side blocks concaved, a plate on the central block of greater width than said central block, plates on the side blocks of greater width than the side blocks and extending inwardly therefrom, and disks located between the central and the side blocks and being of greater diameter than the nearest points of the central block to adjacent points of the side blocks.

In testimony whereof I affix my signature.

OMER J. POULIN.
